WALTER F. KEENAN, JR., OF PELHAM, NEW YORK, ASSIGNOR TO FOSTER WHEELER CORPORATION, OF NEW YORK, N. Y., A CORPORATION OF NEW YORK

FURNACE WALL

Application filed May 27, 1926, Serial No. 111,908, and in Great Britain April 10, 1926.

My present invention relates to fluid cooled furnace walls, and the general object of the invention is to provide improvements in construction and arrangement especially devised and adapted for use under the severe conditions to which the so-called water back or water cooled wall at the clinker discharge end of a stoker gate are subjected. More specific objects of the invention are to provide improved means for supporting water back conduit elements and for providing the necessary heat insulating effect, and preventing gas leakage adjacent the elbow portions of said elements when the later are the type comprising bare tubes having furnace wall lining portions surrounded by sectional cast iron casings, and having transverse end portions which extend through the outer portion of the furnace wall and are connected to external headers.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of the invention.

Of the drawings:

Fig. 1 is a diagrammatic sectional elevation of a boiler furnace; 35 Fig. 2 is a horizontal section the upper portion being taken on the line 2—2 and the lower portion of which is taken on the line 2A—2A of Fig. 1;

Fig. 3 is an enlarged section taken similarly to Fig. 1;

Fig. 4 is section on the line 4—4 of Fig. 3, with parts broken away and removed;

Fig. 5 is a partial section on the line 5—5 of Fig. 3;

Fig. 6 is a front elevation of a portion of the apparatus shown in Figs. 2, 3, and 4;

Fig. 7 is a sectional elevation illustrating a modified form of water back construction;

Fig. 8 is a view taken similarly to Fig. 7 illustrating a second modification;

Fig. 9 is a horizontal section on the line 9—9 of Fig. 8;

Fig. 10 is a view taken similarly to Fig. 7 illustrating another form of the invention; and

Fig. 11 is a partial section on the line 11—11 of Fig. 10.

In Figs. 1 to 6 of the drawings I have illustrated a preferred form of water back construction employed in a boiler A conventionally illustrated as of the vertical tube or Stirling type. The boiler A, as shown, comprises water tubes B connecting a lower water drum B' to upper steam and water drums B², the water tubes being traversed by products of combustion coming to them from a combustion chamber A' at the bottom of which is located a stoker grate C. C' represents the clinker discharge passage, the upper portion of the front wall of which is formed by the metallic apron C², and the upper portion of the rear wall of which is formed by a water cooled wall, or water back formed by vertically disposed elements E which are incorporated in and line a portion A³ of the furnace wall.

The water back elements E comprise bare tubes e having vertically disposed body portions and transverse end portions connecting the body portions to the external water back inlet and outlet headers E' and E², respectively. The water back is connected into the boiler water circulating system by means of downcomer piping E³ connecting header E' to the drum B', and riser piping E⁴ connecting the header E² to the front drum B². The body portion of each tube e is surrounded by a sectional casing formed of perforated cast iron blocks E⁵ and end sections E⁶ and E⁷ which are advantageously iron bodies cast in place on the tubes e after the casing sections E⁵ of the latter have been shrunk in place and the end portions of the tube transversely bent. The body portions of the elements E ordinarily are vertically disposed, though in many installations they are advantageously not exactly vertical, but inclined slightly to the vertical as shown in Fig. 1. When the body portions of the elements are of any considerable length the tendency of the elements

to warp or become deformed under the conditions of use is advantageously restrained by stiffening bars F suitably connected to the elements. As shown in Figs. 1 and 3, the 5 stiffening bars F are connected by bolts to lugs secured on the back sides of some of the sections E⁶.

The furnace wall A³ in front of which the water back is located, lies beneath the 10 bridge wall A² and supports the latter through iron work. This iron work as shown in Figs. 1 to 5, comprises a steel beam G and transverse beams H shown as of I-beam cross section and spaced apart to provide openings in the wall through which the upper 15 transverse end portions of the tubes e extend. The lower end portions of the elements extend through openings in the furnace wall formed by incorporating therein elements h 20 generally similar to the elements H. Ordinarily a water back of the character shown in Fig. 3, is suspended by supporting means engaging the elements at their upper ends, and suitable clearance provisions must be 25 made to permit the lower ends of the elements to rise and fall as the elements elongate and contract in response to temperature changes. In the construction shown in Figs. 1 to 6, the 30 elements E are supported by fins or plate-like iron or steel ribs I which are welded to the under sides of the horizontal upper end portions of the tubes E and which rest on the top of the I-beam G.

With the type of water back construction 35 and mounting in the furnace wall shown in Figs. 1-6, it is necessary to protect the I-beam G and beams H against exposure to furnace temperatures, and it is, of course, necessary to prevent air and gas leakage 40 through the openings in the furnace wall proper formed to receive the end portions of the tubes e. To this end ribs or fins K formed by suitably shaped pieces of metal plate are welded to the convex side of the 45 upper elbow portion of each tube e. Advantageously, as shown in Fig. 3, these ribs K are shaped to have vertical front edges in substantial alignment with the heat absorbing face of the water back, and to have top 50 edges which abut against the portion of the underside of the bridge wall A² in front of the beams G and H which are overhung by the bridge wall. Advantageously, and as 55 shown, the ribs K are formed with registering apertures receiving horizontal reinforcing bars L. The spaces between the adjacent fins K and between the adjacent portions of the tubes e are filled with refractory material M which might be formed of fire brick 60 or tile, but advantageously is a known kind of refractory cement or plastic fire brick which can be put into place while in an initial putty-like condition and which when subjected to the heat of the combustion chamber A' in the regular operation of the boiler 65

sets and acquires considerable mechanical strength, and heat resisting properties analogous to those of ordinary fire bricks. The material M may be formed of ground fire brick, and a clay binder. This material when 70 heated becomes hard and strong enough to aid materially in supporting the overhanging portion of the bridge wall particularly when, as in the construction shown in Fig. 6, the material M is worked snugly into place 75 between the portion of the underside of the bridge wall in front of the beams G and H and the inner base flange of the beam G. The material assists in supporting the bridge wall not only directly but indirectly through the 80 lateral support and rigidity which it gives to the fins K which bear at their upper sides directly against the underside of the bridge wall.

In putting the material M into place it is 85 tamped or hammered with a mallet to eliminate voids and to insure full contact with the surfaces engaged, and particularly with the sides of the fins K and the portions of the tubes e surrounded by the material. The 90 strength and effectiveness of the material M in use is maintained by the cooling action of the fins K and elements E on the material M which prevents the latter from being heated to an injuriously high temperature. The 95 effectiveness of the cooling action on the material M of the contacting portions of the elements E and fins K is enhanced, of course, by the closeness of the contact. The material 100 M protects the upper elbow portions of the tubes e against flame impingement and prevents leakage through the furnace wall adjacent to the top of the water back and effectually protects the iron work G and H against overheating.

The lower cast-on casing sections E⁷, and the subjacent portion A³⁰ of the wall A³, may 105 be shaped to provide only the necessary mechanical clearance to accommodate thermal expansion and contraction between the 110 lower ends of the blocks E⁷ and the wall portion A³⁰. Gas leakage through the spaces between the transverse beams h may be prevented by a packing O of kieselguhr or the like, or formed by some refractory cement 115 which is sufficiently yielding to accommodate the movements of the adjacent metallic portions of the water back without developing cracks through which air or gas leakage can occur. A known form of cement of this 120 character is composed mainly of mineral wool plus some asbestos and a suitable binder.

The modified water back construction 125 shown in Fig. 7, is practically identical with that shown in Figs. 1 to 6, except that in Fig. 7 the water back is suspended through an angle bar P bolted to the upper cast arm casing blocks E⁶. The bottom flange of the channel bar P rests on a metal plate Q incorporated in the wall A³, which, as shown, in 130

this construction, comprises a masonry portion A³¹ at the outer side of the bar P which replaces the beam G of the construction first described and supports the beams H.

5 In the construction shown in Figs. 8 and 9, the portion of the furnace wall A² above the water back is carried by beams GA which support metallic parts HA and HA' replacing the beams H of the construction previously described. The parts HA are in the form of open cast iron boxes with a central web parallel to the length of the beams GA. The central webs and the end walls of the box-like parts HA are perforated for the passage of the out-turned end portions of the tubes e. Suitable packing material O' which may be like the material O previously referred to, is placed in each box at the outer side of its central web. The parts HA' are cover plates resting on the parts HA and directly supporting the wall A². The lower end portions of the tubes e pass through box-like parts ha similar to the parts HA, and supporting cover plates ha' which in turn, support the portion of the wall A³ above them. In this construction, however, the wall A³ extends but a short distance above the cover plates ha'. Gas leakage through the joints between the elements E, and heat radiation losses from the outer sides of the elements are prevented by a facing of refractory cement R plastered on the outer sides of the elements. The facing R may be made of the same material as the cement packing material O previously referred to. The facing R extends as shown, between the elbow portions of the tubes e at the top and bottom of the elements E, and contacts at its upper end with the material M packed between the fins K and about the upper elbow portions of the tubes e.

45 Figs. 8 and 9 also illustrate an expedient which may be employed when for any reason adjacent elements E are separated by a considerable space. This expedient consists in filling the space between the separated elements by material MA which may be similar to the material M, and may be reinforced when necessary as by means of a reinforcing bar S suspended from one of the bars L and centered by metal parts S' positioned in turn by bars S² in the facing R. In the construction shown in Figs. 8 and 9, the material MA replaces one element E omitted because the header E² is divided into sections as indicated at E²⁰ so that it would not be readily possible to make header connections to an element in front of the abutting ends of the two header sections.

50 Figs. 10 and 11 illustrate another modification in which the portion of the furnace wall above the water back is supported by a structural beam GB through transverse beams H as in the construction first described, and in which as in Figs. 8 and 9,

there is no brick wall at the outer side of the water back. In this construction the water back instead of being suspended is supported by the engagement of the lower casing blocks E' with the subjacent portion A³⁰ of the masonry wall A³, and the ribs KA welded to the convex sides of the upper elbow portions of the tubes e, are on the furnace side of, and project above the lower edge of the wall A². With this construction the upper portions of the water back move relative to the wall A³ as the result of thermal expansion and contraction, and to prevent gas leakage through the spaces between the transverse beams H those spaces are filled with a packing material OA which may be similar to the packing material O previously described. In the constructions shown in Figs. 10 and 11, gas leakage through the joints between adjacent elements is prevented by packing material RA which may be similar to the packing material O first described, which fills the space between the rear sides of the elements E, and a metal sheathing at the outer side of the elements.

55 In a co-pending application, Serial No. 111,945, filed of even date herewith, I have disclosed and claimed a furnace wall in which the wall cooling body portions of the conduits are covered at their furnace chamber sides by refractory material supported and cooled by longitudinal ribs like the ribs K herein described but prolonged to extend along the body portions of the tubes.

60 While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

65 Having now described my invention, what I claim as new and desire to secure by Letters Patent, is:

1. In a fluid cooled furnace chamber wall, the combination with conduit elements each comprising a metal tube having a wall lining body portion and a transverse wall penetrating end portion having an integral fin at its furnace chamber side, and refractory material in the spaces between the fins of adjacent elements.

70 2. In a fluid cooled furnace wall, the combination with conduit elements each comprising a tube having a wall lining body portion and an end portion, a metallic casing for said body portion and a metal fin secured to the furnace chamber side of said end portion, and refractory material placed between and supported and cooled by the fin portions of adjacent elements.

3. In a fluid cooled furnace chamber wall, the combination with wall cooling metal conduits, of means for restricting the heat absorption by portions of said conduits comprising refractory material, and metal fins secured to said conduit portions at the furnace chamber side thereof supporting and cooling said refractory material placed between said fins.
- 10 4. In a fluid cooled furnace chamber wall, the combination with wall cooling metal conduits each having a portion exposed for a portion of its length at the furnace chamber side, refractory material covering the furnace chamber side of another portion of each conduit, and a metal projection carried by each last mentioned conduit portion at the furnace chamber side supporting and cooling said refractory material.
- 15 5. In a fluid cooled furnace chamber wall, metal wall cooling conduits each exposed for a portion of its length at the furnace chamber side, refractory material covering another portion of each tube and a metal fin welded to the furnace chamber side of the last mentioned portion of each tube and supporting and cooling said refractory material.
- 20 6. In a fluid cooled furnace chamber wall, the combination with wall cooling conduits each having a portion with a relatively thick wall exposed at the furnace chamber side and another portion of smaller wall thickness, of a fin welded to the last mentioned conduit portion at its furnace chamber side and refractory material supported and cooled by the fin portions of the different tubes.
- 25 7. A fluid cooled furnace wall comprising a tube having a straight body portion, and transversely extending portions connected to the body portion by curved elbow portions, a metallic casing surrounding the body portion of said tube, and metal fins welded to and projecting radially away from the convex sides of said elbow portions.
- 30 8. In a fluid cooled furnace wall, conduit elements each comprising a bare tube having a straight body portion and transverse end portions adapted to project outward from the wall, and metal fins welded to the convex sides of said elbow portions.
- 35 9. In a fluid cooled furnace wall, conduit elements each comprising a bare tube having a straight body portion and transverse end portions adapted to project outward from the wall, and metal fins welded to the convex sides of said elbow portions, and refractory material in the spaces between said fins and in contact with said end portions.
- 40 10. In a fluid cooled furnace wall, conduit elements each comprising a bare tube having a straight body portion and transverse end portions adapted to project outward from the wall, and metal fins welded to the convex sides of said elbow portions, and refractory material in the spaces between said fins and
- 45 5. In a fluid cooled furnace chamber wall, in contact with said end portions, and reinforcing bars connecting said fins.
- 60 11. A fluid cooled furnace wall comprising tubes having vertically disposed body portions united to form a furnace wall lining, and transverse wall penetrating end portions, and means for supporting said tubes adjacent their upper ends, said means comprising metal fins welded to the undersides of the upper transverse end portions.
- 65 12. In a fluid cooled furnace wall, the combination with conduit elements each comprising a metal tube having a wall lining body portion and a transverse wall penetrating end portion of radial fins of metal welded to the furnace chamber sides of said end portions, and refractory material in the spaces between said fins and in contact with said end portions.
- 70 13. A fluid cooled furnace wall comprising a tube having a straight body portion, and transversely extending portions united to the body portion by curved elbow portions, metallic casing blocks shrunk in place on the body portion of said tube, and metallic casings for said elbow portions cast in place thereon.
- 75 14. In a fluid cooled furnace wall, conduit elements each comprising a bare tube having a straight body portion and transverse end portions adapted to project outward from the wall and connected to the body portion by curved elbow portions, metal casing sections snugly secured to the body portion of each element and uniting to provide a smooth heat absorbing wall lining, and metal casing sections for said elbow portions cast in place upon the latter.
- 80 15. In a furnace chamber wall, the combination with a lower wall portion, a water back lining said wall portion, and a wall portion overhanging said lining, said water back comprising tubes each having a vertically disposed body portion and an out-turned upper end portion, of a metallic casing for the body portion of each tube, a plate-like fin welded to each of said end portions and having its upper edge extending into contact with said overhanging wall portion and having its front edge substantially flush with the heat absorbing wall formed by the furnace chamber sides of said casing sections.
- 85 16. In a furnace chamber wall, the combination with a lower wall portion, a water back lining said wall portion, and a wall portion overhanging said lining, said water back comprising tubes each having a vertically disposed body portion and out-turned upper end portion, of a metallic casing for the body portion of each tube, an apertured plate-like fin welded to each of said end portions and having its upper edge extending into contact with said overhanging wall portion and having its front edge substantially flush with the heat absorbing wall formed by the furnace chamber sides of said casing sections.

chamber sides of said casing sections, re-inforcing bars received in the apertures in adjacent fins, and refractory material molded into place between said fins and about said 5 re-enforcing bars and in contact with said end portions and the upper ends of said casings.

17. In a furnace chamber wall having an upper portion and a lower portion overhung 10 by said upper portion, spaced metal conduits having vertically disposed body portions in front of said lower wall portion and transverse portions at their upper ends penetrating said lower wall portion, metal casings surrounding said body portions, metal fins welded to the furnace chamber sides of said end portions adjacent the upper ends of said casings and projecting upward into contact with the overhanging upper wall portion, and refractory material located in the spaces 15 between said fins at the furnace chamber side 20 of the wall.

Signed at New York city, in the county of New York and State of New York, this 18th 25 day of May, A. D. 1926.
